[57] CLAIM

The ornamental design for a golf club head face, substantially as shown and described.

DESCRIPTION

FIG. 1 is a front elevation of a golf club head face showing our new design;

FIG. 2 is a section on lines 2—2 of FIG. 1;

FIG. 3 is a section on lines 3—3 of FIG. 1;

FIG. 4 is a front elevation of a modified form of the golf club head face.

The broken line showing of a golf club head is to indicate environment only and the dominant feature of our design resides in the full line portion of the face.
